UNITED STATES PATENT OFFICE.

CHARLES DE LOS RICE, OF HARTFORD, CONNECTICUT, ASSIGNOR TO
UNDERWOOD TYPEWRITER COMPANY, OF NEW YORK, N. Y., A COR-
PORATION OF NEW JERSEY.

TYPE-BAR GUIDE FOR TYPE-WRITERS OR LIKE MACHINES.

SPECIFICATION forming part of Letters Patent No. 735,152, dated August 4, 1903.

Application filed March 13, 1903. Serial No. 147,577. (No model)

To all whom it may concern:

Be it known that I, CHARLES DE LOS RICE, a citizen of the United States, and a resident of Hartford, county of Hartford, and State of 5 Connecticut, have invented certain new and useful Improvements in Type-Bar Guides for Type-Writers or Like Machines, of which the following is a specification.

My invention relates to type-writers and 10 like machines, and particularly to the means employed for guiding the type-bar adjacent to the printing-point, and has for its object to provide a simple construction of the above- indicated character which will be capable of 15 ready adjustment, so that the type-bars may be correctly guided to the printing-point.

I so construct my improved guide that the adjustment may be made when the machine is first assembled and may be corrected, if 20 necessary, at any time during the life of the machine.

One form of my invention will now be described with reference to the accompanying drawings, and the novel features will then 25 be pointed out in the appended claims.

Figure 1 is a front elevation of the type-bar- carrying segment of a type-writing machine, together with my improved type-bar guide attached thereto. Figs. 2, 3, and 4 are sec- 30 tional views taken on the lines 2 2, 3 3, and 4 4, respectively, of Fig. 1. Fig. 5 is a cross- section on line 5 5 of Fig. 2. Fig. 6 is a detail face view of a nut employed in my in- 35 vention, and Fig. 7 is a plan of the guide and segment.

A indicates the segment, on which the type- bars are fulcrumed in any approved manner.

B is the type-bar guide, which is located at the top edge of the segment A and which at 40 its upper end is formed with the forwardly- projecting arms B', the adjacent surfaces of which flare forwardly, so as to form a guide for the type-bar toward the printing-point. It will be understood that the printing-point 45 is in the central plane indicated by the line 3 3 in Fig. 1. The arms B' project from the upper ends of fork members B², which are separated from each other by a vertical slit B³, preferably provided at its lower end and 50 also, if desired, near its upper end with en-

largements B⁴. By this construction the fork members B² are given elasticity, so that they will have a tendency to move toward each other. The fork members B² and guide members B', which are thus movable transversely 55 in relation to each other, may be spread apart by means of an expanding-screw C, which engages both members and has a conical head C', so that as the screw is screwed in the fork members B² will be moved farther apart. To lock the fork members in their adjusted position and to assist the inward movement produced by their resiliency, I provide a screw D, which connects the fork members B² transversely, as shown best in 60 Fig. 5. It will be understood that this connecting-screw D extends across the slot B³, while the expanding-screw C extends into the said slot.

The means so far described enable the 70 width of the slot B³ or, in other words, the distance between the guide-arms B' to be adjusted. In order to enable the guide-arms B' to be leveled, I provide the following ar- 75 rangement: The body B of the guide has at 75 a distance below the vertical slot B³ two horizontal slots B⁵, provided at their inner ends with enlargements B⁶. Into these slots are adapted to fit screws E, having conical heads E' and also lugs F', projected from nuts 80 F, into which the said screws E are adapted to screw. The opposing surfaces of the lugs are beveled to correspond to the conical face of the screw-head. The body of the nut is received within a slot or recess A' of the seg- 85 ment A. It will be understood that the lugs F' prevent the nuts F from turning relatively to the guide-body B. Thus when the screw E is turned it will have a tendency to crowd the upper wall of the slot B⁵ upward, since 90 the lower portion of the body B is rigidly se- cured to the segment A, as by screws G.

The slots B⁵ give a resiliency to the por- tions B⁷, located above them, and these por- 95 tions practically form movable arms capable of a movement which may be described as approximately a pivotal movement the cen- ter of which is adjacent to the intersection of the lines 3 3 and 4 4 in Fig. 1.

Now supposing the left-hand screw E is re- 100

leased and the right-hand screw E is tightened, the entire portion of the guide which is above the slots B⁵ will be swung in the direction of the arrow in Fig. 1, thus changing 5 the position of the top line of the guide relatively to a horizontal plane. It will therefore be obvious that by releasing one of the screws E and tightening the other the type-bar guide may be leveled, so that the slot B³ 10 will be exactly vertical and the upper faces of the arms B' exactly horizontal.

It will be understood that various departures may be made from the construction shown without sacrificing the advantages of 15 my invention.

The adjustment of the distance between the guide-arms B' and the leveling of said arms will of course be made at the factory when the machine is assembled for shipment; 20 but if any change of adjustment should be required after the machine has been used this can be readily done without taking the machine apart.

What I claim as new, and desire to secure 25 by Letters Patent, is—

1. A type-bar guide comprising two guide members movable toward and from each other, an expanding-screw having a flaring portion adapted to engage both of said members, and another screw connecting said members transversely.

2. A type-bar guide comprising two resilient guide members movable toward and from each other, and having a tendency to move 35 toward each other, and an expanding-screw arranged between said members and engaging both of them.

3. A type-bar guide comprising two resilient guide members having a tendency to 40 move toward each other, an expanding-screw arranged between said guide members and adapted to spread them apart, and another screw connecting said guide members transversely and adapted to hold them in their ad-45 justed position.

4. A type-bar guide comprising guide members movable toward and from each other, an adjusting-screw located between said members and controlling the distance between 50 them, and means for holding the guide members in their adjusted position.

5. A type-bar guide comprising resilient guide members, an expanding-screw located between said members and arranged to spread 55 them apart against their resiliency, and another screw connecting said members transversely to hold them in their adjusted position.

6. A type-bar guide comprising a stationary

guide-body, a guide proper movably connected therewith, and adjusting means for rigidly connecting said guide-body with the guide proper, so that normally the guide proper will be stationary and rigid with the 60 guide-body. 65

7. A type-bar guide comprising a stationary body portion and a guide portion proper movably connected with said body portion to swing so as to allow the guide proper to be leveled.

8. A type-bar guide comprising a stationary 70 body portion, a guide portion movably connected with said body portion, and expanding-screws arranged between said portions to adjust the guide portion relatively to the body portion.

9. A type-bar guide comprising a stationary body portion, a guide portion connected with said body portion and having arms extending at a slight distance from adjacent edges of the body portion, forming slots therewith, and 80 adjusting-screws arranged in said slots.

10. A type-bar guide provided with a vertical slot, whereby two adjacent resilient guide members are formed, and also provided with horizontal slots whereby a body portion 85 is separated from a guide portion yieldingly connected with said body portion, and means arranged in the said slots for adjusting the distance between the guide members, and for adjusting the guide portion relatively to the 90 body portion.

11. A type-bar guide having two members movable toward and from each other and separated by a slot, a nut provided with lugs projecting into said slot to prevent the nut from 95 turning, and an expanding-screw fitting into said nut and in engagement with said members to adjust the distance between them.

12. The combination with the type-bar segment of a type-writing machine, or the like, 100 said segment having recesses adjacent to the printing-point, of a type-bar guide having a body portion secured to the segment below said recesses, and a guide portion arranged above said body portion and separated therefrom by horizontal slots, nuts located in said recesses of the segment and provided with lugs projecting into said slots, and expanding-screws arranged to fit the said nuts and to engage the walls of said slots to adjust the 105 guide portion relatively to the body portion.

In testimony whereof I have hereunto set my hand in the presence of two subscribing witnesses.

CHARLES DE LOS RICE.
